POWER WRINGER AND THE LIKE

Walter L. Kauffman, II, Erie, Pa., assignor to
 Lovell Manufacturing Company, Erie, Pa., a
 corporation of Pennsylvania

Application May 13, 1938, Serial No. 207,705

4 Claims. (Cl. 68—263)

Power wringers and similar devices involve a certain amount of hazard to persons operating them in that there is danger of the operator getting caught in the rolls. In order to reduce 5 the hazard to some extent, devices have been provided for relieving the pressure on the rolls and where such pressure is released for safety, or in ordinary use, it is desirable to reset the pressure. The present invention is designed to 10 improve the wringer or similar device as to its releasing and resetting means. Features and details of the invention will appear more fully from the specification and claims.

A preferred embodiment of the invention is 15 illustrated in the accompanying drawing, wherein the invention is exemplified as a wringer.

Fig. 1 shows a front elevation of a wringer partly in section, with the wringer parts in set 20 position.

Fig. 2 a front elevation of the wringer showing the releasing and resetting devices in position to react the pressure means of the wringer.

Fig. 3 a section on the line 3—3 in Fig. 1. 1 marks the bottom of the wringer frame; 25 2 one of the side stiles; and 3 the opposite side stile. 4 and 5 mark wringer rolls; 6 and 7 shafts for said rolls respectively. Bearings 8 for the lower shaft are mounted and fixed in the stiles. Bearings 9 for the upper shaft are 30 slidingly mounted in the stiles. A spring 10 operates on the upper bearings. A screw 11 adjusts the pressure of the spring. A nut 12 receives the screw, the nut being mounted in a movable top bar 13. The top bar is of channel 35 form with closed ends. A shoulder 14 is formed in one of the stiles and this is engaged by shoulder 15 struck up in the end of the top bar. These shoulders hold the top bar in set position, but 40 permit the other end of the top bar to lift, and with the lifting, detach the connection through the shoulders 14 and 15.

A toggle has the links 16 and 18 the link 16 being pivoted at 17 on the top bar and the link 18 being pivoted at 19 on the stile 2 and at 20 45 on the link 16. The link 18 is doubled, or duplicated, on each side of the stile. The link 16 is of channel form, providing the side 16a to which the links 18 are attached. The pivot at 17 is in the form of a pin which extends through 50 the top bar and through the side 16a of the link 16. A releasing and resetting lever 21, preferably of channel form having the side plates 21a, is pivoted on the pin 17, the side plates extending between the sides 16a and the sides of the 55 top 13. The link 16 is arc formed at its upper

end and is provided with an inturned shoulder 23 at the end of the arc formed portion. A shoulder 24 is bent up on the end of the lever 21 in position to engage the shoulder 23 when the lever 21 is moved in response to downward pressure, the position of these shoulders with the wringer in set position being shown in Fig. 1. The lever 21 also has a shoulder 25 struck up in its outer face, which shoulder is adapted to engage the shoulder 23 when the lever 21 is 10 forced upwardly in the resetting operation.

In resetting the wringer, both hands of the operator may be used, as illustrated in Fig. 2. The lever 21 therefore assists in response to 15 upward pressure and the link 16 responds to downward and inward pressure, both tending to swing the toggle links into alignment so as to draw down the top bar and thus reset the pressure on the spring 10. As shown, the toggle links are carried slightly beyond dead center so as to 20 stabilize the connection in set position.

With the parts in set position as shown in Fig. 1, should the operator become caught or should a release of the pressure be desired for any purpose, this may be accomplished by striking 25 downwardly on the handle at the end of the lever 21. This swings the link 16 outwardly so as to bring the pivots past dead center and thus break the toggle. The lever 21 should have sufficient clearance with relation to the top bar 30 to effect this movement of the link 16 past the center. In resetting the toggle, the lever, through its pivotal but limited movement, can be swung upwardly so as to bring the shoulder 25 into engagement with the shoulder 23. This, in effect, 35 makes the lever 21 an extension of the link 16 so that an upward and outward pull of the lever 21 may be realized in resetting the links, or it may be used in assisting in resetting the links where pressure is also exerted on the links 16 40 as shown in Fig. 2. The lost motion between the link 16 and the lever 21 permits the link 16 to swing out freely after the links are carried past dead center. Without this lost motion the lever 21 in its normal set position would not be 45 in the most desirable position for effecting a release.

What I claim as new is:

1. In a wringer having a frame, rolls mounted in the frame, a movable top bar for the frame, 50 pressure means exerting pressure from the top bar on the rolls, and a toggle connection between the frame and top bar, the links of the toggle swinging on axes extending from front to rear of the wringer, the toggle when set holding the 55

- top bar in position to set the pressure on the rolls and releasing the top bar when the toggle is broken, the combination with the toggle and top bar, of means actuating the toggle comprising a lever having a lost motion connection with a link of the toggle and swinging therewith in the plane of the axes of the rolls to actuate the toggle, said lever in set position extending over and lengthwise along the top bar and movable downward toward the top bar to release the toggle.
2. In a wringer having a frame, rolls mounted in the frame, a movable top bar for the frame, pressure means exerting pressure from the top bar on the rolls, and a toggle connection between the frame and top bar, the links of the toggle swinging on axes extending from front to rear of the wringer, the toggle when set holding the top bar in position to set the pressure on the rolls and releasing the top bar when the toggle is broken, the combination with the toggle and top bar, of means actuating the toggle comprising a lever having a lost motion connection with a link of the toggle and swinging therewith in the plane of the axes of the rolls to actuate the toggle, said lever in set position extending over and lengthwise along the top bar and movable downward toward the top bar to release the toggle, said lever having means engaging the link which in reverse movement of the lever will cause resetting of the toggle and the pressure means.
3. In a wringer having a frame, rolls mounted in the frame, a movable top bar for the frame, pressure means exerting pressure from the top bar on the rolls, and a toggle connection between the frame and top bar, the links of the toggle swinging on axes extending from front to rear of the wringer, the toggle when set holding the top bar in position to set the pressure on

the rolls and releasing the top bar when the toggle is broken, the combination with the toggle and top bar, of means actuating the toggle comprising a lever having a part in underlying relation to a part on a link of said toggle providing a lost motion connection with said link of the toggle and swinging therewith in the plane of the axes of the rolls to actuate the toggle, said lever in set position extending over and lengthwise along the top bar and movable downward toward the top bar to release the toggle, said lever having means engaging the link which in reverse movement of the lever will cause resetting of the toggle and the pressure means, and permitting through the lost motion connection a continued release movement of the toggle independently of the lever.

4. In a wringer having a frame with a bottom and side stiles, rolls mounted in the frame, a movable top bar for the frame, pressure means exerting pressure from the top bar on the rolls, and a toggle connection between the frame and the top bar, one link of the toggle being of channel form with its sides pivoted to the top bar and the other link of the toggle being connected to a side stile, the axes of the links extending from front to rear of the wringer, the combination with the toggle and top bar, of means actuating the toggle comprising a lever of channel shape, the sides of the lever and the channel sides of the channel formed link of the toggle being arranged with the sides of one underlying the sides of the other and having a lost motion connection therewith, said lever swinging therewith in the plane of the axes of the rolls to actuate the toggle.

WALTER L. KAUFFMAN, II.
